ELECTRIC SWITCH

Filed March 16, 1928

Inventor:
George Stern,
by Charles E. Yulla
His Attorney

UNITED STATES PATENT OFFICE.

GEORG STERN, OF OBERSCHONEWEIDE, NEAR BERLIN, GERMANY, ASSIGNOR TO GENERAL ELECTRIC COMPANY, A CORPORATION OF NEW YORK.

ELECTRIC SWITCH.

Application filed March 16, 1928, Serial No. 262,227, and in Germany March 30, 1927.

My invention relates to electric switches of the liquid break explosion chamber type. Switches of this type are commonly constructed with metal explosion chambers, usually steel, in which is mounted the fixed contact and in which initially occurs any arc that is drawn by the withdrawal of the movable contact. To prevent the arc from striking to the chamber which is in electrical connection with the fixed contact the chamber usually has been covered with a fibrous insulating material in the form of cylinders, plates, bushings, etc. In certain cases I have found that such insulation is not sufficient to prevent an arc from forming between the movable contact and the metal of the chamber, particularly when a breaking by the arc first drawn has been immediately followed by an excess voltage. The movable contact being still relatively close to the chamber, an arc has become established between the moving contact and the chamber through the joints in the insulation thereon. An object of my invention, therefore, is to provide an improved switch of the type described which shall avoid the objectionable action mentioned above.

My invention will be better understood from the following description taken in connection with the accompanying drawing, and its scope will be pointed out in the appended claims.

Referring to the single figure of the drawing, which is a sectional view illustrating an embodiment of my invention, the switch comprises the fixed contact 1 shown in the form of a socket and the movable contact 2 shown as a rod adapted when raised to closed circuit position to engage in the socket of contact 1. The fixed contact 1 is enclosed by the explosion chamber 3 comprising the top plate 4 and the cup-like member 5, members 4 and 5 being shown secured together by screw threads. Although not shown in detail on the drawing it will be understood that means are provided for making a circuit connection with the fixed contact 1 and for securing this contact to the top plate 4 which means are well known to those familiar with electrical switches of this type. The member 5 thus is in electrical connection with the contact 1. In the bottom of member 5 is an opening through which the contact rod 2 is moved to engage the fixed contact and

through which it is withdrawn in the opening movement of the switch. In accordance with my invention, I provide the explosion chamber with the covering 6 of insulation which is seamless throughout its extent. It covers all those portions of member 5 to which there is any danger of an arc striking from the contact rod 2. As shown in the drawing, the insulation extends in a continuous layer over both the inside and the outside surfaces of member 5 and through the opening in the bottom thereof. For thus insulating the explosion chamber I employ preferably an insulating material which may be applied in the plastic form and which becomes rigid. I have found an insulating material comprising an asbestos composition with a suitable binder such as a synthetic or natural resin and known to the trade as "Tenazit" to be well suited for this purpose, the material being molded to the member 5 while subjected to heat. If it is found that the insulating material under certain conditions requires protection from the heat of the arc it is obvious that a covering of suitable material may be applied thereto. The seamless insulating material 6 need be used only on those portions of the explosion chamber to which there is danger of an arc striking, other parts of the switch which require insulation being insulated in any well known and suitable manner.

What I claim as new and desire to secure by Letters Patent of the United States, is:—

1. In an electric switch of the liquid break type, a fixed contact, a cooperating movable contact rod, and an explosion chamber enclosing the fixed contact and having an opening for receiving the contact rod, said chamber having insulating material thereon extending in a seamless covering over the exterior through the opening and over the interior.

2. In an electric switch of the liquid break type, an explosion chamber having an opening therein, a fixed contact within and electrically connected with the chamber, a cooperating contact rod adapted to be withdrawn from the fixed contact through said opening, and means for preventing an arc becoming established between the contact rod and the chamber comprising a seamless covering of insulation applied to those parts of the chamber to which the arc is liable to strike.

3. An electric switch of the liquid break type comprising a fixed contact, a cooperating movable contact, and an explosion chamber enclosing the fixed contact and having an opening therein for receiving the movable contact, said explosion chamber having a seamless covering of insulating material

comprising asbestos and resin extending through the opening and over adjacent inner and outer portions of the chamber. 10

In witness whereof, I have hereunto set my hand this 24th day of February, 1928.

GEORG STERN.
